United States Patent Office

Des. 193,741
Patented Oct. 2, 1962

193,741

JAR

Claire J. Westhoven, Toledo, Ohio, and Richard E. Brown, Decatur, Ga., assignors to Owens-Illinois Glass Company, Toledo, Ohio, a corporation of Ohio

Filed Mar. 29, 1961, Ser. No. 64,537

Term of patent 14 years

(Cl. D58—25)

FIG. 4

The sides not shown are the same as the sides shown.

We claim:

The ornamental design for a jar, substantially as shown and described.
